THREAD HOLDING AND CUTTING DEVICE
FOR SHOE SEWING MACHINESDana P. Hay, Beverly, Mass., assignor to United
Shoe Machinery Corporation, Flemington, N. J.,
a corporation of New Jersey

Application July 30, 1947, Serial No. 764,865

4 Claims. (Cl. 112—252)

1

The present invention relates to shoe inseam sewing machines and more particularly to improvements in thread cutting and holding devices similar to those disclosed in United States Letters Patent No. 1,396,066, granted November 8, 1921, on application of Thomas H. Seely, and No. 2,200,402, granted May 14, 1940, upon application of Victor J. Tetrault.

The machines disclosed in the patents referred to are equipped with thread cutters so arranged that after the sewing operation is completed the shoe is removed from the machine, withdrawing a length of thread connecting the end of the seam in the shoe with the stitch forming devices and the shoe is given a second upward movement to engage the thread with a thread holder and then a third movement in a different direction to carry the thread against the edge of a thread cutting knife. In the machine of the Seely patent the shoe, after being disengaged from the machine, is moved, first along the line of the seam to withdraw thread, then upwardly and in the reverse direction to engage the thread with the thread holder and then downwardly to sever the thread. In the machine of the Tetrault patent it is necessary to reverse the movement of the shoe in a horizontal direction after engaging the thread with the cutting knife to cause the thread to be severed. While the movements required to produce the desired results are relatively short and consume a small fraction of a second only, these movements when taken together add up to an appreciable effort as compared to the total expenditure of both time and energy for a complete day's output of work.

It is accordingly an object of the present invention to provide a thread holding and cutting device for a shoe inseam sewing machine by means of which the thread may safely be severed much closer to the end of a seam in a shoe than with prior thread cutting devices and with a minimum number of movements of the shoe after being withdrawn from the machine.

In the illustrated form of the invention the machine is provided with a device having opposed thread gripping jaws disposed with flaring spaced ends forming a throat which faces a shoe being operated upon in the machine to admit lateral entry of the sewing thread during upward movement of the shoe from the point of operation. As hereinafter described, a thread cutting knife is provided with a cutting edge extending generally in the direction of the seam being sewn and facing rearwardly and a projecting portion disposed in front of the cutting edge of the knife

5 to guard the shoe from injury by the cutting edge while the thread is being severed. By this arrangement the shoe may be brought into actual contact with the projecting portion of the cutting device without danger of injury before the thread is severed, after which an extremely short movement of the shoe will sever the thread sufficiently close to the end of the seam to avoid the necessity of further trimming.

10 These and other features of the invention as hereinafter described and claimed consist in certain devices, combinations, and arrangements of parts, the advantages of which will readily be understood from the detailed description taken in connection with the accompanying drawings.

In the drawings,

Fig. 1 is a view in right-hand side elevation of the forward portion of a shoe inseam sewing machine embodying the features of the present invention;

20 Fig. 2 is a detail view on an enlarged scale in front elevation of the thread cutting device, the looper and a portion of a shoe being operated upon illustrated in Fig. 1 indicating the end of thread about to be released at the start of a new seam; and

25 Fig. 3 is a view in side elevation of the same parts, the thread cutting position of the shoe being shown in dot-dash lines.

30 The machine illustrated in the drawings is the same, except as hereinafter described, as that of United States Letters Patent No. 1,108,560, granted August 25, 1914, upon application of Andrew Eppeler and No. 1,971,575, granted August 28, 1934, upon application of Alfred R. Morrill.

35 The machine is equipped with a curved hook needle 2, an awl 4, a looper 6, a channel guide 8, a welt guide 10, a back rest 12, a take-up 14 and other stitch forming devices more fully described in the Eppeler and Morrill patents. These devices act to insert a chain stitch inseam within an upper 16 and a ribbed insole 18 and usually a welt (not shown). The welt when used is drawn into the angle between the rib and feather of the insole to bring the welt and upper into conformity with the angle. After completion of the seam the shoe is withdrawn from the sewing point a short distance to the left to cause a free length of thread to be measured between the shoe and the looper sufficient to enable a new seam to be started without difficulty.

40 In the machine of the Seely and Tetrault patents referred to, the length of thread for starting a new seam is held yieldingly within the grasp of a pair of gripping jaws disposed with their spaced

free ends facing away from the point of sewing operation toward the left of the machine. In order to introduce the thread to the gripping jaws of the patented machines, the shoe must be drawn to the left of the sewing point beyond the gripping jaws and the direction of shoe movement reversed to bring the thread while held taut between the shoe and the looper laterally between the spaced ends of the jaws. After engagement of the thread with the jaws of the patented machines the shoe is moved still further toward the right until the thread is carried against the edge of the cutting knife. To sever the thread in the Tetrault machine the shoe must again be reversed in its movement to tighten the thread against the cutting edge of the knife. Such an arrangement has been considered necessary heretofore for reliable gripping and cutting results. Furthermore, when the shoe is carried to the right to bring the thread into engagement with the cutting edge of the knife it is difficult to gage the length of thread between the cutting edge of the knife and the shoe, since this length of thread is determined by the distance through which the shoe is withdrawn to the left of the machine before engagement with the gripping jaws.

In the machine of the present invention the shoe is moved upwardly and somewhat to the left after the seam has been completed and engaged in a single movement with the gripping jaws during continued upward movement of the shoe rather than during a definite additional movement of the shoe to the right as in prior machines. After engagement of the thread with the gripping jaws in the present machine the thread is brought against the cutting edge of the knife during continued upward movement of the shoe. To sever the thread in the present machine, therefore, it is necessary only to continue the upward movement of the shoe and to pull it somewhat forward of the machine, as indicated by the dot-dash lines in Fig. 3, movement to the right being avoided or reduced to an inappreciable minimum. The cutting edge of the knife in the present machine also is located closer to the gripping jaws for the thread than in prior machines so that it is easier to gage the length of thread required for effective gripping and severing of the thread while withdrawing the shoe from the machine.

The thread gripping jaws of the illustrated machine are similar to those of the machine in the Tetrault patent and consist of a pair of elongated plates 20 and 22 having flaring spaced ends forming a throat to receive the thread. The jaw plates are secured to a supporting block 24 by means of clamping bolts 26 passing through the plates and into threaded engagement with the block. The bolts 26 also pass through the shank of a thread cutting knife blade 28 to form a backing for the bolts. The block 24 in turn is secured to the frame of the machine by clamp screws passing through openings 30 in the block, the arrangement of the thread gripping plates being such that they are inclined downwardly toward a shoe being sewn and somewhat to the left of the sewing point.

The thread cutting knife blade 28 has its shank portion extending parallel to the gripping jaw plates 20 and 22 and is provided with slotted openings 32 for the clamping bolts 26 to permit easy removal of the knife merely by loosening the bolts. The cutting edge of the knife, however, extends generally parallel to the line of the seam

inserted by the machine and faces rearwardly with a bend of approximately right angles to the shank, forming between the cutting edge and the shank a projecting abutment portion which acts as a guard against which the shoe may bear during the thread cutting operation.

The sequence of movements imparted to the shoe at the end of a seam in the machine of the present invention includes first a movement to the left to withdraw thread from the looper 6 sufficient in length to enable a new seam to be started, and a second single upward movement to engage the thread laterally between the thread gripping jaws and to bring the thread against the cutting edge of the knife 28. For the purpose of gaging accurately the length of thread end remaining on the shoe a third movement of the shoe may be made to bring the shoe into actual contact with the abutment formed by the bend in the knife blade. The surfaces of the shoe within the angle of the sewing rib and the feather on the insole engage the bend and a rolling action is imparted to the shoe utilizing the abutment as a fulcrum. After engagement of the shoe with the abutment a uniformly accurate position relatively to the knife is insured so that the knife will act close to the end of the seam in the shoe, the actual severing force being applied to the thread during the rolling action. It will thus be noted that engagement of the thread in the gripping jaws of the thread holder and the severance of the thread may be accomplished with great accuracy in two more or less continuous movements without requiring a definite reversal of movement as in prior machines. Furthermore, by utilizing the abutment on the device as a gage the thread remaining connected with the shoe may be made uniformly short to avoid the necessity of further trimming while at the same time leaving an end of adequate length to start a new seam.

The nature and scope of the invention having been indicated and a particular embodiment having been described, what is claimed is:

45. 1. A machine for sewing an inseam to connect a ribbed insole and an upper of a shoe having stitch forming devices, in combination with a thread holder provided with opposed gripping jaws pressed yieldingly toward each other and disposed with flaring spaced ends forming a throat which faces toward the shoe being operated upon to admit lateral entry of the sewing thread extending between the sewn shoe and the stitch forming devices in a single upward movement of the shoe while being withdrawn from the machine.

60. 2. A machine for sewing an inseam to connect a ribbed insole and an upper of a shoe, having stitch forming devices and a thread holder provided with opposed gripping jaws pressed yieldingly toward each other and disposed with spaced ends facing the shoe being operated upon to admit lateral entry of the sewing thread extending between the sewn shoe and the stitch forming devices in a single movement of the shoe while being withdrawn from the machine, in combination with a thread cutter at the front of the machine above the sewing point having a knife extending generally parallel to the line of the seam inserted by the machine, the cutting edge of which faces rearwardly, and a projection disposed in front of the cutting edge of the knife, serving as an abutment to guard the shoe from injury by the cutting edge while severing the thread.

70. 3. A machine for sewing an inseam to connect

a ribbed insole and an upper of a shoe, having stitch forming devices and a thread holder provided with opposed gripping jaws pressed yieldingly toward each other and disposed with spaced ends facing the shoe being operated upon to admit lateral entry of the sewing thread extending between the sewn shoe and the stitch forming devices in a single movement of the shoe while being withdrawn from the machine, in combination with a thread cutter at the front of the machine above the sewing point having a knife blade, the shank of which extends parallel to the gripping jaws and the cutting edge of which faces rearwardly at an angle to the shank to form between the cutting edge and the shank a projecting portion in front of the cutting edge to guard the shoe from injury by the cutting edge while severing the thread.

4. A machine for sewing an inseam to connect a ribbed insole and an upper of a shoe, having stitch forming devices and a thread holder provided with opposed gripping jaws pressed yieldingly toward each other and disposed with spaced ends facing the shoe being operated upon to admit lateral entry of the sewing thread extending between the sewn shoe and the stitch forming devices in a single movement of the shoe while

being withdrawn from the machine, in combination with a thread cutter at the front of the machine above the sewing point having a knife blade, the shank of which extends parallel to the gripping jaws and the cutting edge of which faces rearwardly at an angle to the shank to form between the cutting edge and the shank a projecting portion in front of the cutting edge to guard the shoe from injury by the cutting edge while severing the thread, the projecting portion of the knife blade being bent and formed to fit the angle between the rib and feather of the shoe, the bend extending along a line at an angle to the cutting edge of the knife to guard the shoe from the cutting edge during movement of the shoe about the bend.
